United States Patent Office.

LORENZO W. ROATH, OF LEXINGTON, OHIO.

Letters Patent No. 80,668, dated August 4, 1868.

IMPROVED BEDSTEAD.

The Schedule referred to in these Letters Patent and making part of the same.

TO ALL WHOM IT MAY CONCERN:

Be it known that I, LORENZO W. ROATH, of Lexington, in the county of Stark, and State of Ohio, have invented certain new and useful Improvements in Bedsteads; and I do hereby declare that the following is a full and complete description of the same, reference being had to the accompanying drawings, making a part of this specification, in which—

Figure 1 is a top view of the bedstead.

Figure 2 a side view of the same.

Like letters of reference refer to like parts in the several views.

In fig. 2, A represents the bed-posts, to which the side and foot-rails, B C, are attached in the ordinary way. To the inside of the rails are secured cleats, D, in which is arranged a series of knobs, E, around which the cord F is drawn, thereby making the bottom of the bed.

It will be observed that the said bottom is in two sections, G and H, section G being secured rigidly in place, whereas section H is not, but which consists of a frame, I, fig. 2, placed within the sides of the bedstead, and attached to section G by means of the cord and angular articulation at the point a, which consists of a deep notch, b, cut in the ends of the cleats of the rigid section, and a corresponding point, c, fitted to the same, whereby section H can be raised to the position as shown in fig. 2, and supported thus by the stay or brace J.

The extended limb of the angle b serves as an axial point on which the upturning section moves, and against which it is stayed when turned up.

In order to preserve the tension of the cord when the bottom is turned up, the said cord is secured to the cross-rail K, fig. 1, by means of the loops d, through which it is drawn; hence there can be no slackening of the cord in consequence of the bottom being elevated.

Its tension, by this means, is fully retained, whatever may be the degree of elevation given to the bottom, and which may be more or less, by resting the end of the brace J in the notches e.

I am aware that bed-bottoms are so constructed that they can be elevated to any particular height, but such beds are usually made with slats for the bottom, and laid transversely; but I am not aware that a corded bed has ever been so made that it can be turned up as above indicated and described.

What I claim as my invention, and desire to secure by Letters Patent, is—

The cross-rail K, loops d, as arranged in combination with the cord F and sections H G, substantially as and for the purpose set forth.

LORENZO W. ROATH.
